GARDEN RAKE

Lyle Gransden, Edenville, Mich. 48620

Filed May 9, 1967, Ser. No. 7,039

Term of patent 14 years

(Cl. D39—1)

FIG. 1 is a perspective view of a garden rake showing my new design with the handle fragmentarily shown;

FIG. 2 is a side elevation thereof; the handle member is broken away to indicate indeterminate length; and

FIG. 3 is a top plan view thereof.

I claim:

The ornamental design for a garden rake, substantially as shown and described.
